METHOD OF OPERATING ELECTROLYTIC CELLS

Einar Sorensen, Rumford, Maine, assignor to
Oxford Paper Company, a corporation of
Maine

Application June 23, 1936, Serial No. 86,725

1 Claim. (Cl. 204—58)

This invention relates to electrolytic cells for producing chlorine and sodium hydroxide from brine of the type disclosed in my prior Patent #1,613,966, issued January 11, 1927, and more particularly to the method of operating such a cell.

The cell disclosed in my prior patent comprises a casing having a longitudinal partition which divides the cell into a decomposing compartment and an oxidizing compartment. Brine, to be treated, enters the decomposing compartment, the floor of which is covered with a slowly moving layer of mercury which constitutes a cathode. Graphite plates located above the mercury constitute the anode. Electric current passing between the graphite plates and the mercury liberates chlorine from the brine and the mercury forms an amalgam with the sodium of the brine. The amalgam flows out of the decomposing compartment into the oxidizing compartment where it passes over notched graphite plates. Measured quantities of water are fed into the oxidizing compartment. By the action set up in the oxidizing compartment the amalgam is decomposed and the sodium reacts with the water to form sodium hydroxide solution. The mercury thus freed of its sodium then enters a pump chamber in which a rotary pump lifts the mercury and returns it to the decomposing compartment.

In the operation of electrolytic cells of the kind described above hydrogen gas is liberated during the reaction that takes place in the oxidizing compartment. The hydrogen gas escaping from the cell entrains some of the caustic. This results in a small loss of caustic but a more serious consequence is that the caustic entrained by the escaping hydrogen contaminates the cell room atmosphere.

The object of this invention is to provide a method of operating a cell of the general type described above that will prevent the entrainment of caustic by the escaping hydrogen gas.

This is accomplished by providing a liquid seal for the oxidizing compartment by maintaining on the body of caustic a floating layer of a liquid which will permit the hydrogen gas to escape through it but which will hold back any caustic which tries to escape with the hydrogen.

An electrolytic cell capable of being operated by my method is shown in the accompanying drawings, but it is to be understood that the method is applicable to cells differing very materially from the one illustrated. The particular cell shown in the drawings is an improvement on the cell shown in my prior patent above referred to and certain features not claimed herein are claimed in my co-pending applications, Serial No. 43,027, filed October 1, 1935, Serial No. 81,344, filed May 23, 1936, Serial No.

93,580, filed July 31, 1936 and Serial No. 97,884, filed August 26, 1936.

In the drawings:

Figure 1 is a plan view of the cell with the cover and the anode assembly of the decomposing compartment removed to expose to view the interior construction of this compartment;

Fig. 2 is a longitudinal section through the decomposing compartment taken on the line 2—2 of Fig. 1. In this view the cover and the anode assembly are in place;

Fig. 3 is a longitudinal section through the oxidizing compartment taken on the line 3—3 of Fig. 1;

Fig. 4 is a detailed sectional view of one end 15 of the oxidizing compartment taken on the line 4—4 of Fig. 1;

Fig. 5 is a sectional view similar to Fig. 4 taken on the line 5—5 of Fig. 1;

Fig. 6 is a transverse section taken on the line 20 6—6 of Fig. 1;

Fig. 7 is a transverse section taken just to the rear of the section of Fig. 6, i. e., on the line 7—7 of Fig. 1;

Fig. 8 is a transverse section taken just to the rear of the section of Fig. 7, i. e., on the line 8—8 of Fig. 1, and

Fig. 9 is a transverse section taken on the line 9—9 of Fig. 1.

The cell illustrated in the drawings has an external metal casing 1 which is generally rectangular in shape as shown in Fig. 1. It is divided into two compartments by a longitudinal partition 2. One of these compartments, designated 3, is the decomposing compartment and the other one designated 4 is the oxidizing compartment. As best shown in Figs. 6 to 9, inclusive, that part of the metal casing which houses the oxidizing compartment projects downwardly to a lower level than the part of the casing which houses the decomposing compartment. This is indicated at 5 in Figs. 6 to 9. The metal casing is lined along the inside walls and over the bottom with concrete 6 and is properly molded to form the various passages and seals hereinafter described.

Brine to be treated enters the decomposing compartment through an inlet 7 (Figs. 1 and 2). The mercury enters the decomposing compartment from the oxidizing compartment at 8 and passes in a thin layer over the bottom of the decomposing compartment, following a tortuous passage through the channels 45, 46 and 47 and is discharged through the passage 9 into the oxidizing compartment. The direction of flow of the mercury is indicated by the arrows in Fig. 1. The mercury in the decomposing compartment forms the cathode of an electric circuit, the anode being graphite plates 10 supported with their lower faces just above the surface of the mercury. As the mercury passes through the

decomposing compartment it forms an amalgam with the sodium of the brine, and the spent brine together with the liberated chlorine is discharged through an outlet 11 located at the proper elevation to maintain the desired depth of brine within the decomposing compartment.

In the oxidizing cell the mercury amalgam passes over the notched graphite plates 12. Measured quantities of water are fed into this compartment by means to be hereinafter described to maintain in this compartment a predetermined density and to compensate for the water consumed in the displacement action. The displacement action which takes place in this cell frees the amalgam of its sodium and causes the sodium to unite with the water to form sodium hydroxide solution. The sodium hydroxide solution is withdrawn from the oxidizing compartment through a pipe 13 (Figs. 1 and 9) which discharges into the lower end of receptacle 14. This receptacle has a vertical partition 15 dividing it into two compartments. The sodium hydroxide solution enters the bottom of the right hand compartment (as viewed in Fig. 1) and flows over the upper edge of the partition 15 into the left hand compartment. It is then discharged through an outlet pipe 16 in the bottom of the left hand compartment. In the right hand compartment there may be located a hydrometer 17 (Fig. 9) by which the density of the sodium hydroxide solution may be measured. The level of the sodium hydroxide solution in the oxidizing compartment is determined by the elevation of the upper edge of the partition 15. Therefore, the level of the sodium hydroxide solution in the oxidizing compartment may be varied, if desired, by raising or lowering the receptacle 14 and thereby raising or lowering the elevation of the upper edge of the partition 15. This may be effected by providing the pipe 13 with a removable section 18 which may be replaced by a longer or shorter section.

The mercury freed of its sodium passes into a pump well 19. A rotary pump 20 lifts the mercury from the well and discharges it at a higher elevation where it flows into the passage 8 of the decomposing compartment thereby completing the cycle. The pump has a series of peripheral pockets 21 (Fig. 6) to which the mercury is admitted through peripheral openings 22. It is discharged from these pockets through openings 23 (Figs. 7 and 8) in the lateral wall of the pump. It is then caught in the manner herein-after to be described and passed on to the decomposing compartment. The mercury pump is operated by a sprocket wheel 24 connected by means of a chain 25 (Fig. 6) to a sprocket wheel 26 (Fig. 3) on a drive shaft 27 driven in any suitable manner.

The water to be supplied to the oxidizing compartment first enters a receptacle 28 through a pipe 29. A pipe 30 having an elbow 31 at its outer end, which forms a small bucket, is oscillated so that it dips down into the water in the receptacle 28 and then as the pipe rises the water flows through the pipe and is discharged from the inner end 32 of the pipe into another compartment 33 of the receptacle 28. The pipe 30 is mounted on a horizontal shaft 34 to the outer end of which is connected an arm 35. This arm is engaged and deflected by a projection 36 associated with the sprocket wheel 24 so that every time the sprocket wheel makes one revolution the pipe 30 is lifted to scoop up a small portion of water and dump it in the compartment 33. From

the compartment 33 the water passes through a pipe 37 directly into the pump well 19. The pump picks up both the mercury and the water and the manner in which the water and mercury are separated so that the water is delivered to oxidizing compartment and the mercury delivered to the decomposing compartment will be hereinafter described.

The anode plates 10 are rigidly fastened to, and suspended from, the cover 53 of the decomposing compartment and form a unit therewith. Each anode plate is rigidly secured to the cover 53 by a graphite lead 57 threaded at both ends. The lower end of the lead 57 is screwed into the anode 10, as shown at 58 and the upper end of the lead passes through an opening in the cover 53 and is clamped to the cover by a fibre nut 59. In the particular cell shown in the drawings there are three anode plates in each channel thus making nine all together. The three anode plates of each traverse row are electrically connected by means of a metallic conducting strip 60 (Figs. 2 and 9) which is secured to the graphite leads 57 by means of stud bolts 61. Three bus bars 62 conduct current to the three traverse rows of anodes.

Current is supplied to the mercury cathode in the decomposing compartment as follows: Embedded in the concrete floor of the decomposing compartment are a series of transversely extending metal bars or strips 63 (Figs. 1 and 2). These are supplied with current by a bus bar 64. Bolt terminals 64a are screwed and welded to the transverse bars 63 and extend through the metal container and are secured to the bus bar 64 by means of nuts 64b. Over each metal bar 63 the concrete floor is provided with a series of holes 65 by means of which the mercury makes contact with the bar. The path of the current is therefore from the bus bar 64 to the bolts 64a, to the transverse bars 63, then to the mercury cathode, through the brine to the graphite anodes 10, then through the leads 57 and connecting strips 60 to the bus bars 62.

After the mercury leaves the decomposing compartment and before it enters the oxidizing compartment it forms a seal and thereby prevents brine from passing from the decomposing compartment to the oxidizing compartment. This seal is therefore called the "brine seal" and is constructed as follows: At the right hand end of the oxidizing compartment 4 (as viewed in Fig. 1) there is a pit or well 70 molded in the concrete lining. In plan view this well is relatively narrow longitudinally of the cell and is relatively long transversely of the cell. The bottom of the well is tapered to form a V as shown at 71 in Fig. 9, the taper being in such a direction that the mercury passing from the decomposing compartment through the passage 8 will flow down one of the arms of the V.

The well 70 forms one of the chambers of the brine seal, the other chamber, shown at 72, (Figs. 1 and 3) being a pit located in the floor of the oxidizing compartment. The bottom of the well 70 communicates with the pit 72 through an opening 73 extending through the wall 74 that separates the well 70 from the oxidizing compartment. It is obvious from this arrangement that a body of mercury will be maintained in the chambers 70 and 72 of the seal at a constant level. As the mercury is continuously fed into the well 70 it is continuously discharged from the pit 72 into the oxidizing compartment. The body of mercury maintained in this manner by the seal 7

chambers 70 and 72 prevents any brine from entering the oxidizing compartment. It will be noted that the mercury enters the well 70 in the lengthwise direction of the well but 5 in a direction transverse to the axis of the opening 73. The mercury thus passing into the well 70, down one side of the V-shaped bottom, and partly up its other side has its velocity spent. This prevents brine from being entrained with 10 the mercury as it passes into the oxidizing compartment thus maintaining purity of the sodium hydroxide solution produced in the oxidizing compartment. The well 70 also serves as a concentration point for any broken up or dispersed 15 mercury as well as any precipitated graphite from the anodes. This concentrated material can be easily removed during operation of the cell which greatly lengthens the time of operation possible between wash-ups. It is important to concentrate 20 and remove the dispersed or broken up mercury for otherwise it will pass into the oxidizing compartment through the seal and may entrain some of the brine. Furthermore, any dispersed mercury which finds its way into the 25 oxidizing compartment will remain in suspension in the sodium hydroxide solution and pass off with it thereby causing a continuous loss of mercury. The outer wall of the well 70 has a normally closed pipe 75 extending through it 30 which communicates with the interior of the well and affords a convenient outlet for the wash water during washups. Moreover, by discharging the wash water through the pipe 75 it is prevented from entering the oxidizing compartment.

35 In passing from the oxidizing compartment into the pump well, the mercury forms a second seal called the "caustic seal" because it prevents caustic from passing along with the mercury to the pump well. This seal comprises a pit 77 40 molded in the concrete floor of the oxidizing compartment and a pit 78 molded in the concrete floor of the pump well (Figs. 3 and 5). Communication between these two pits is established by a passage 79 in the wall 80 which separates the 45 oxidizing compartment from the pump well. The body of mercury maintained in the chambers 77 and 78 at a constant level constitutes a seal similar to the one previously described. As the mercury is continuously fed into the compartment 77 it is continuously discharged from 50 the compartment 78 into the well of the mercury pump but no caustic can pass into the pump well.

As previously stated the rotary mercury pump 55 picks up the mercury in the pump well and also the water which has been fed to the pump well by the water bucket 31 already described. The mercury and water, discharged through the lateral openings 23 in the side wall of the pump, 60 falls into a transverse trough 81 (Figs. 1, 3, 5, and 7), which conducts them to a third mercury seal called the "water seal" because it prevents the water from passing along with the mercury into the decomposing compartment. This seal 65 is formed by pits 82 and 83 molded in the concrete and a connecting passage 84 which places the bottom of these pits in communication (Figs. 1, 3, 4, 5, 6, and 7). As the mercury is continuously fed into the pit 82 it is continuously discharged over the edge 85 of the pit 83 (Fig. 6) and then passes into the transverse passage 8 which conducts the mercury to the first channel 45 of the decomposing compartment. The water held back by the seal 82-83-84 and which 70 floats on top of the mercury as it passes through

the trough 81 is conducted through a short passage 86 and discharged directly into the oxidizing compartment (Figs. 1 and 8).

The trough 81 is so arranged as to minimize 5 splash of the mercury as it is discharged from the pump 20. Splashing of the mercury at this point would be harmful as it would cause breaking up or dispersing of the mercury or would also augment vaporization. Prevention of vaporization of the mercury is very important from a 10 health standpoint. A spill plate 87 (Figs. 1 and 3) extends from the bottom of the trough 81 to a point closely adjacent the discharge outlets 23 of the pump to prevent spill of the mercury back into the pump well. The water in the 15 trough 81 (supplied by the oscillating bucket 31 to the pump well and delivered by the pump to the trough 81) acts as a cushion for the falling mercury. It also acts as a wash and a submerging cover for the mercury during its travel to 20 the water seal 82-83-84.

As previously described the oscillating water bucket 31 supplies a uniform and measured quantity of water to the oxidizing compartment. As the water is first delivered to the pump well it 25 keeps the mercury in the pump well and in the pockets of the pump covered with water and thereby prevents vaporization of the mercury and the consequent contamination of the room atmosphere.

In the oxidizing compartment hydrogen gas 30 is liberated when the sodium is freed from the amalgam and reacts with the water to form sodium hydroxide solution. The hydrogen gas is usually permitted to escape to the cell room atmosphere and in so doing entrains a small 35 amount of caustic. In order to prevent entrainment of caustic by the liberated hydrogen gas I maintain on the body of caustic in the oxidizing compartment a liquid seal shown at 76 in Fig. 3. 40 The liquid floats on the surface of the caustic and permits the hydrogen gas to bubble through it but holds back any caustic which would otherwise be entrained by the escaping hydrogen gas. Prevention of entrainment of caustic by the 45 hydrogen gas which is liberated to the cell room atmosphere is an important consideration from a health standpoint. It also decreases the loss of caustic.

It will be noted from the foregoing description 50 of the structural features of the cell that the cell is so constructed and arranged as to maintain in the oxidizing compartment a body of caustic solution having sufficient depth to prevent the liquid 78 floating on its surface from contacting with the mercury on the floor of the oxidizing compartment. This is made clear in Fig. 3 55 of the drawings. As above stated the level of the caustic in the oxidizing compartment can be adjusted by varying the elevation of the upper edge of the partition 15 in the caustic discharge receptacle 14.

The liquid employed for the seal should be lighter than the caustic solution so that it will 60 float upon it, and it should have sufficient fluidity to enable the hydrogen to escape through it. The material used for the liquid seal should preferably possess the following additional characteristics; inertness with respect to the caustic, immiscibility in caustic and water and inability to 65 emulsify with either, a sufficiently high boiling point to prevent excessive vaporization and freedom from metallic impurities which would otherwise contaminate the caustic and the mercury. I have found that a hydrocarbon mineral 70

oil is suitable for the purpose and have successfully used such an oil having the following specifications:

5 Type of base Paraffin
5 Viscosity at 100° F. Saybolt universal test, 85/90
seconds
Gravity (density) A. P. I. test, 27/27.5 degrees
Flash 340° F.
Impurities None

10 I claim:
The method of operating an electrolytic cell
of the type which has a decomposing compartment

ment and an oxidizing compartment through
which mercury may be circulated, which comprises producing and maintaining a body of caustic solution in the oxidizing compartment, and
maintaining on the surface of the caustic solution a layer of hydrocarbon mineral oil which
is inert with respect to the caustic and which
has sufficient fluidity to permit gas produced
in the oxidizing compartment to escape through
it whereby the entrainment of caustic by the escap- 10
ing gas is prevented.

EINAR SORENSEN.
